DESIGN FOR A TABLECLOTH OR SIMILAR ARTICLE

John S. Madsen, New York, N. Y.

Application February 9, 1940, Serial No. 90,154

Term of patent 3½ years

To all whom it may concern:

Be it known that I, John S. Madsen, a citizen of the United States of America, residing in the city of New York, county of New York, and State of New York, have invented a new, original, and ornamental Design for a Tablecloth or Similar Article, of which the following is a specification, reference being had to the accompanying drawing, forming part thereof.

The figure in the drawing shows a tablecloth or similar article showing my new design. The dot and dash lines indicating one half section thereof, the other half being identical therewith arranged in proper relation to complete the cloth.

I claim:

The ornamental design for a tablecloth or similar article, substantially as shown and described.

JOHN S. MADSEN.
